UNITED STATES PATENT OFFICE.

MORGAN L. GROVER, OF LAVALLE, WISCONSIN.

WASHING-MACHINE.

SPECIFICATION forming part of Letters Patent No. 327,159, dated September 29, 1885.

Application filed October 2, 1884. (Model.)

To all whom it may concern:

Be it known that I, MORGAN L. GROVER, of 45
Lavalle, in the county of Sauk and State of
Wisconsin, have invented a new and Improved
5 Washing-Machine, of which the following is a
full, clear, and exact description.

This invention relates to certain new and 10 useful improvements in that class of washing-
machines in which a rocking clothes box or
15 tub is provided and the clothes are washed
and cleaned by rocking the said tub, all as
hereinafter fully described, and pointed out
in the claims.

Reference is to be had to the accompanying 20 drawings, forming part of this specification, in
which similar letters of reference indicate cor-
responding parts in both the figures.

Figure 1 is a longitudinal elevation of my 25 improved washing-machine, parts being
broken out and parts in section; and Fig. 2 is
a cross sectional elevation of the same on the
line *x x*, Fig. 1.

A box or tub, A, having segmental sides, 30 has a curved bottom, B.

The box A is held to crossed braces C, uniting 35 semicircular or like rockers D, with top
bars, E, uniting the ends of the rockers, and
provided with upwardly or horizontally pro-
jecting handles E', either straight or curved.
40 The box or tub A is thus held between two
rocking frames, with which the said tub or
box can be rocked.

The top F of the box A is provided with a 45 tight-fitting cover, F', and directly below the
cover a transverse shaft, G, is journaled in the
box, from which a swinging beater extending
across box A is suspended.

The beater is formed of a bottom bar, a, 50 having the cross-section of a truncated cone, a
cylindrical bar, b, above the bar a, an oval
bar, c, above the bar b, and a diamond-shaped
bar, d, at the top of the bars, decreasing in
thickness, size, and cross-section from the bot-

tom to the top. They are suspended by a rope
or cord, l, from the shaft G.

In place of the bars described, bars of any
other desired cross-section may be used.

Transverse boards B', having grooves h, are 55 secured on the inner surface of the bottom B
at the middle and ends. The bottom bars of
the beater H are grooved longitudinally on all
sides.

Spaces B² are formed between the under
sides of the boards B' and the inner surface of
the bottom, through which spaces the water 55
passes, thus causing an under current, which
keeps the clothes loosened and throws them
against the grooves at the end of the box.

The clothes are placed in the box or tub A
with a sufficient quantity of hot soap-suds, the 60
cover F' is closed tightly, and the box A is
rocked. The clothes are thrown from one
end of the same to the other, and are beaten
by the swinging beater H.

The clothes are cleaned very rapidly, and 65
comparatively little power is required for op-
erating the machine.

Having thus described my invention, I claim
as new and desire to secure by Letters Patent—

1. In a washing-machine, the combination, 70
with the box or tub A, of the rockers D, the
top bars, E, and the braces C, uniting the top
bars and rockers, and to which braces the box
A is secured, substantially as herein shown
and described.

2. In a washing-machine, the combination, 75
with the box or tub A, of the transverse
grooved boards B', secured on the inner sur-
face of the bottom, the swinging flexible beater
H, and rockers secured to the tub or box, 80
substantially as herein shown and described.

MORGAN L. GROVER.
